(57) **ABSTRACT**

The disclosure provides an audio processing device comprising a first filter and a second filter. The first filter is configured to generate a first filtered signal based on an error signal, the error signal representative of audible sound at a target space. The second filter is configured to generate a second filtered signal based on the error signal. An anti-noise signal is generated based on the first filtered signal and the second filtered signal, and the anti-noise signal is included in the error signal. The first filter is connected to the second filter in parallel.

AUDIO PROCESSING DEVICE

This application claims the benefit of U.S. provisional application Ser. No. 63/287,561, filed Dec. 9, 2021, the subject matter of which is incorporated herein by reference.

TECHNICAL FIELD

The disclosure relates to an electronic device, and more particularly, relates to an audio processing device for noise reduction.

BACKGROUND

As progressing of technology related to wireless communication, headphone (i.e., earphone or headset) capable of communicating in a wireless manner has fulfilled the demand of mainstream market. During playing audio (e.g., phone call voice or music sound) to a user, the headphone provides a noise cancellation mechanism to suppress unwanted noise. The noise cancellation mechanism refers to, for example, an advanced noise cancellation (ANC). However, the existing noise cancellation techniques cannot effectively suppress unwanted noise. It is desirable to develop an audio processing device for reducing undesirable interference signals.

SUMMARY

According to one aspect of the disclosure, an audio processing device is provided. The audio processing device comprises a first filter and a second filter. The first filter is configured to generate a first filtered signal based on an error signal, the error signal representative of audible sound at a target space. The second filter is configured to generate a second filtered signal based on the error signal. Wherein an anti-noise signal is generated based on the first filtered signal and the second filtered signal, and the anti-noise signal is included in the error signal, and wherein the first filter is connected to the second filter in parallel.

BRIEF DESCRIPTION OF THE DRAWINGS

FIG. 1A is a schematic diagram illustrating an audio processing device applied to a headphone according to an example of the disclosure.

FIG. 1B is a schematic diagram illustrating an audio processing device applied to an earphone according to another example of the disclosure.

FIG. 2 is a block diagram of the audio processing device in FIGS. 1A and 1B.

FIGS. 3A and 3B are equivalent sampled-time block diagrams illustrating equivalent transfer function of the audio processing device of FIG. 2.

FIG. 4 is a spectrum diagram illustrating spectrum analysis for transfer functions of various examples of audio processing devices of the disclosure.

FIGS. 5A to 5E are block diagrams illustrating transfer functions of various examples of audio processing devices, according to the spectrum diagram of FIG. 4.

FIG. 6A is a schematic diagram illustrating an audio processing device applied to a headphone according to another example of the disclosure.

FIG. 6B is a schematic diagram illustrating an audio processing device applied to an earphone according to still another example of the disclosure.

FIG. 7A is a block diagram of the audio processing device in FIGS. 6A and 6B.

FIG. 7B is a block diagram of yet another example of audio processing device of the disclosure.

FIG. 7C is a block diagram of further another example of audio processing device of the disclosure.

FIG. 8 is a block diagram of further another example of audio processing device of the disclosure.

In the following detailed description, for purposes of explanation, numerous specific details are set forth in order to provide a thorough understanding of the disclosed embodiments. It will be apparent, however, that one or more embodiments may be practiced without these specific details. In other instances, well-known structures and devices are schematically illustrated in order to simplify the drawing.

DETAILED DESCRIPTION

20 In the noise cancellation mechanism, feedback (FB) units or feedforward (FF) units are employed. The FB and FF units take at least environmental noise as an error signal or a reference signal to achieve noise reduction. However, transfer function of circuits including the FB or FF units may have poles at certain frequencies, and such poles will lead to unstable status and cause a "howling" phenomena. Furthermore, over-shoot of the transfer function will lead to undesirably "added-on" of noise.

FIG. 1A is a schematic diagram illustrating an audio processing device 1000 applied to a headphone 3000 according to an example of the disclosure. Referring to FIG. 1A, the audio processing device 1000 is disposed in the headphone 3000 to provide an anti-noise signal to reduce influence caused by environmental noise. The headphone 3000 of FIG. 1A is, for example, an over-ear headphone or a head-mounted headset with an earmuff 3100 over an ear 2000 (e.g., the left-ear) of a user. The audio processing device 1000 refers to an integrated circuit (IC) disposed within at least one of a left-ear part and a right-ear part of the headphone 3000. For simplicity, FIG. 1A merely shows the left-ear part of the headphone 3000.

The earmuff 3100 of the headphone 3000 has an inner side 3101, and the inner side 3101 faces toward the ear 2000 when the earmuff 3100 covers the ear 2000. The headphone 3000 is equipped with a speaker 700 and a first microphone 810 both disposed on the inner side 3101 of the earmuff 3100. Hence, the first microphone 810 is an interior microphone of the headphone 3000, and serves as an error microphone. The audio processing device 1000 provides a cancelling signal y-a to the speaker 700, and the speaker 700 generates a first acoustic signal ac1 based on the cancelling signal y-a. The first acoustic signal ac1 serves as an anti-noise signal to reduce a first noise n1, which is an environmental noise. The environmental noise may be an external noise from environment outside the earmuff 3100, a noise appears between the earmuff 3100 and the ear 2000, an internal noise within a canal of the ear 2000, or a combination of the above all.

In operation, the first acoustic signal ac1 is adjusted based on the cancelling signal y-a, so that the first acoustic signal ac1 ideally has substantially equal amplitude and opposite phase with respect to the first noise n1. When the first acoustic signal ac1 is transmitted along a path from the speaker 700 toward the ear 2000, the first acoustic signal ac1 is superposed by the first noise n1 to form a second acoustic signal ac2. Since the first acoustic signal ac1 and the first noise n1 are substantially equal to each other in amplitude

but opposite in phase, the first acoustic signal $ac1$ may significantly reduce or even entirely eliminate the first noise $n1$, and hence the resulted second acoustic signal $ac2$ may be approximately noise-free. The second acoustic signal $ac2$ is then heard by the ear **2000**, and the user has a noise-free experience.

On the other hand, the first microphone **810** receives the second acoustic signal $ac2$ and generates an error signal $e-a$ based on the second acoustic signal $ac2$. The error signal $e-a$ is representative of audible sound at a target space, for example, ear **2000**. When the first acoustic signal $ac1$ reduces the first noise $n1$ well, the error signal $e-a$ almost reaches a zero-value in amplitude. Such an error signal $e-a$ is then provided for the audio processing device **1000** to adjust the cancelling signal $y-a$ (and may in turn adjust the first acoustic signal $ac1$).

FIG. 1B is a schematic diagram illustrating an audio processing device **1000** applied to an headphone **4000** according to another example of the disclosure. As illustrated in FIG. 1B, the headphone **4000** is depicted as a set of wireless or wired in-ear earbuds (for simplicity, FIG. 1B merely shows a left-ear part of the headphone **4000**). Similar to the example of FIG. 1A, the audio processing device **1000** also refers to an IC disposed within the headphone **4000**. Furthermore, the headphone **4000** is also equipped with a speaker **700** and a first microphone **810**. The headphone **4000** has a plug **4100**, and the plug **4100** has an inner portion **4101** to be fitted into the ear **2000**. The speaker **700** and the first microphone **810** are disposed on the inner portion **4101** of the plug **4100**. The audio processing device **1000** provides the cancelling signal $y-a$ to control amplitude and phase of the first acoustic signal $ac1$ so as to reduce the first noise $n1$. Moreover, the second acoustic signal $ac2$, formed by superposing the first acoustic signal $ac1$ on the first noise $n1$, is employed by the first microphone **810** to generate the error signal $e-a$.

FIG. 2 is a block diagram of the audio processing device **1000** in FIGS. 1A and 1B. Referring to FIG. 2, the audio processing device **1000** includes a transmitting (TX) front end **100**, a receiving (RX) front end **210** and a plurality of feedback (FB) units. In the example of FIG. 2, the audio processing device **1000** includes two FB units (i.e., FB units **310** and **320**) coupled in shunt. That is, the FB units **310** and **320** are coupled to each other in parallel. Furthermore, the RX front end **210** is coupled to the FB units **310** and **320** to form a FB path **30**. In an embodiment, the FB units **310** and **320** are implemented by execute instructions stored on a memory, using a processor.

The RX front end **210** is electrically or communicatively coupled to the first microphone **810** to receive the error signal $e-a$. The error signal $e-a$ is an analog signal, and the RX front end **210** is an analog circuitry part of the audio processing device **1000**. The RX front end **210** serves to process the analog error signal $e-a$ to obtain an error signal $e-d$ in digital domain. In one example, the RX front end **210** includes at least a pre-amplifier, an anti-aliasing filter and an analog-to-digital converter (ADC) (not shown in FIG. 2) which function to amplify the error signal $e-a$, remove unwanted harmonics thereof and convert the error signal $e-a$ to the error signal $e-d$ in digital domain. Then, the resulted digital error signal $e-d$ is provided to the FB units **310** and **320** to generate FB signals $b1$ and $b2$. Furthermore, the FB path **30** further includes a mixer **380** functioning to combine the FB signals $b1$ and $b2$ to form a cancelling signal $y-d$.

The error signal $e-d$ serves an “indicator” for evaluating performance of the audio processing device **1000**. When the first acoustic signal $ac1$ well reduces or even eliminate the

first noise $n1$, the error signal $e-d$ is almost zero in amplitude. Each of the FB units **310** and **320** includes filters (not shown in FIG. 2), and the error signal $e-d$ is used to generate input sequence for the filters in the FB units **310** and **320**. Furthermore, the error signal $e-d$ is used to adjust coefficients of the filter in each of the FB units **310** and **320**, so that the FB units **310** and **320** can provide desired FB signals $b1$ and $b2$, respectively. A desired cancelling signal $y-d$ is obtained based on the FB signals $b1$ and $b2$. Subsequently, the cancelling signal $y-d$ is processed by the TX front end **100** to obtain the cancelling signal $y-a$. Similar to the RX front end **210**, the TX front end **100** is another analog circuitry part of the audio processing device **1000**, which may include a digital-to-analog converter (DAC), a reconstruction filter and a power amplifier (not shown in FIG. 2). The TX front end **100** functions to convert the cancelling signal $y-d$ in digital domain into the cancelling signal $y-a$ in analog domain. Then, the speaker **700** generates the first acoustic signal $ac1$ based on the cancelling signal $y-a$.

FIGS. 3A and 3B are equivalent sampled-time block diagrams illustrating equivalent transfer function of the audio processing device **1000** of FIG. 2. Referring to FIGS. 3A and 3B, the FB unit **310** has an impulse response $w1(n)$ representing characteristics of processing behavior performed by the FB unit **310**. The impulse response $w1(n)$ may be transformed to Z-domain as a transfer function $W1(z)$ as depicted in FIGS. 3A and 3B to evaluate the FB unit **310**. Likewise, another FB unit **320** has an impulse response $w2(n)$ representing its behavior, and the FB unit **320** has a corresponding a transfer function $W2(z)$ as depicted in FIGS. 3A and 3B in Z-domain. The overall behavior of the FB units **310** and **320** is evaluated by an equivalent transfer function $Wc(z)$ as expressed in equation (1):

$$Wc(z)=W1(z)+W2(z) \quad \text{eq. (1)}$$

Furthermore, the path from the first microphone **810** to the FB units **310** and **320** through the RX front end **210** is evaluated by an equivalent transfer function $S1(z)$, and the path from the FB units **310** and **320** to the speaker **700** through the TX front end **100** is evaluated by an equivalent transfer function $S2(z)$. The overall path, which starts from output of FB units **310** and **320** and ends at input of FB units **310** and **320**, is evaluated by an equivalent transfer function $Sc(z)$ shown as equation (2):

$$Sc(z)=S1(z)+S2(z) \quad \text{eq. (2)}$$

From the above, an overall transfer function $H(z)$ of the audio processing device **1000** is obtained as equation (3):

$$H(z)=\frac{1}{1+Sc(z)Wc(z)}=\frac{1}{1+Sc(z)[W1(z)+W2(z)]} \quad \text{eq. (3)}$$

In addition, an overall gain Gv of the audio processing device **1000** may be derived from the transfer function $H(z)$. If the portion “ $Sc(z)[W1(z)+W2(z)]$ ” of denominator of the transfer function $H(z)$ has a value equal to minus one (i.e., $Sc(z)[W1(z)+W2(z)]=-1$) at a frequency **F0**, the denominator of transfer function $H(z)$ becomes zero (i.e., $1+Sc(z)[W1(z)+W2(z)]=0$) and the transfer function $H(z)$ has a “pole” at frequency **F0**, which leads the audio processing device **1000** to an unstable status. At such a frequency **F0**, the audio processing device **1000** has infinite overall gain Gv so that the first noise $n1$ is infinitely amplified and a “howling” phenomena is caused. To alleviate such a “howling”, two or more FB units **310**, **320**, etc., are disposed in the audio

processing device **1000**. The more the number of FB units **310**, **320**, etc. are employed, the better prevention for “howling” are achieved.

On the other hand, if the transfer function $H(z)$ has a magnitude greater than one (i.e., $|H(z)| > 1$) at some other frequencies (or in some frequency range), the first noise $n1$ is also undesirably amplified by the audio processing unit **1000**. In this case, “over-shoot” of the transfer function $H(z)$ may be observed in spectrum analysis, indicating that first noise $n1$ is undesirably “added-on”. For the audio processing device **1000** of the disclosure, disposing more number of FB units **310**, **320**, etc. may also help to alleviate such “noise add-on”.

In further detail, generally, for a noise cancellation device, it is desired to have relatively broad bandwidth. However, an unwanted add-on phenomena and an unwanted howling phenomena are likely to occur as the bandwidth is increased. The bandwidth cannot be increased indefinitely in consideration of at least the add-on and howling phenomena.

Some existing approaches uses a single FB unit. The equivalent transfer function $Sc(z)$ is dominated by the single FB unit. A tuning dimension is accordingly only one and determined by the single FB unit. The bandwidth is relatively narrow about 300 Hz in a given magnitude of about 10 dB on the premise that the add-on and howling phenomena are prevented to occur.

In the present disclosure, at least two FB units are used. The equivalent transfer function $Sc(z)$ is dominated by the at least two FB units. A tuning dimension is accordingly at least two, more than the existing approaches. As a result, the bandwidth is relatively broad about 800 Hz in a given magnitude of about 10 dB on the premise that the add-on and howling phenomena are prevented to occur.

FIG. 4 is a spectrum diagram illustrating spectrum analysis for transfer functions $H(z)$ of various examples of audio processing devices of the disclosure. FIGS. 5A to 5E are block diagrams illustrating transfer functions of various examples of audio processing devices, according to the spectrum diagram of FIG. 4. Firstly, referring to FIGS. 4 and 5A, when the audio processing device **1000** is not equipped with any FB units, transfer function $H(z)$ of the audio processing device **1000** may be obtained as equation (4):

$$H(z) = H0(z) = \frac{1}{1 + Sc(z)} \quad \text{eq. (4)}$$

Regarding curve **C0** of FIG. 4, curve **C0** corresponds to spectrum of $H0(z)$ and represents magnitude of the second acoustic signal $ac2$ of FIG. 2.

Next, referring to FIGS. 4 and 5B, when the audio processing device **1000** is equipped with one FB unit, (e.g., only the FB unit **310**), transfer function $H(z)$ of the audio processing device **1000** is expressed as equation (5):

$$H(z) = H11(z) = \frac{1}{1 + Sc(z)W1(z)} \quad \text{eq. (5)}$$

Curve **C1** of FIG. 4 corresponds to spectrum of $H11(z)$, in which curve **C1** represents magnitude of the second acoustic signal $ac2$. Regarding curve **C1**, at frequency of about 150 Hz the second acoustic signal $ac2$ has a magnitude drop of 22 dB relative to curve **C0**, indicating the first noise $n1$ is significantly reduced. However, at frequency about 680 Hz,

the second acoustic signal $ac2$ has an unwanted magnitude gain of 11 dB relative to curve **C0**, indicating “noise add-on” occurs at 680 Hz.

Next, referring to FIGS. 4 and 5C, when the audio processing device **1000** is equipped with another single FB unit, (e.g., only the FB unit **320**), transfer function $H(z)$ of the audio processing device **1000** is obtained as equation (6). Regarding curve **C2** which corresponds to spectrum of $H12(z)$, “noise add-on” does not occur, for example, from 25 Hz to 680 Hz, in curve **C2**.

$$H(z) = H12(z) = \frac{1}{1 + Sc(z)W2(z)} \quad \text{eq. (6)}$$

Next, referring to FIGS. 4 and 5D, when the audio processing device **1000** is equipped with two FB units **310** and **320** coupled in shunt (in accordance with the example of FIG. 2), transfer function $H(z)$ of the audio processing device **1000** is obtained as equation (7):

$$H(z) = H2(z) = \frac{1}{1 + Sc(z)[W1(z) + W2(z)]} \quad \text{eq. (7)}$$

Regarding curve **C3** which corresponds to the spectrum of $H13(z)$, “noise add-on” does not occur, for example, from 25 Hz to 730 Hz. Furthermore, greater magnitude drop is observed in curve **C3**, (e.g., a drop greater than 22 db appears at 150 Hz, and greater than the embodiment of FIG. 5C). The above spectrum analysis shows that, given the FB units (e.g., FB units **310** and **320**) are coupled in shunt, if the number of FB units increases, better noise reduction will be achieved. Moreover, comparing to curve **C0**, magnitude drop of at least 10 dB occurs from about 25 Hz to about 730 Hz in curve **C3**, and hence spectrum of $H13(z)$ has “10 dB-BW” (i.e., 10 dB-effective-bandwidth) of approximately 700 Hz. Which means, as the number of parallel-coupled FB units increases, greater bandwidth can be also achieved on the premise that the add-on and howling phenomena are prevented to occur.

Next, referring to FIG. 5E, when the audio processing device **1000** is equipped with more FB units (e.g., n ’s FB units) coupled in shunt, transfer function $H(z)$ of the audio processing device **1000** is expressed as equation (8):

$$H(z) = Hn(z) = \frac{1}{1 + Sn(z)[W1(z) + W2(z) + W3(z) + \dots + Wn(z)]} \quad \text{eq. (8)}$$

Though spectrum of $Hn(z)$ is not shown in FIG. 4, theoretical studies and experimental simulations indicate that spectrum of $Hn(z)$ can achieve much greater magnitude drop with respect to **C0** and much wider 10 dB-BW. That is, the more the number of parallel-coupled FB units disposed in the audio processing device **1000**, the greater magnitude drop (i.e., better noise reduction) and the wider 10 dB-BW (i.e., better “howling” prevention) can be achieved.

FIG. 6A is a schematic diagram illustrating an audio processing device **1000b** applied to a headphone **3000b** according to another example of the disclosure. FIG. 6B is a schematic diagram illustrating an audio processing device **1000b** applied to a headphone **4000b** according to still another example of the disclosure.

Referring to FIG. 6A, the headphone **3000b** is similar to the headphone **3000** of FIG. 1A except that, the headphone

3000b is further equipped with a second microphone **820** to receive a second noise **n2**. The earmuff **3100** of the headphone **3000b** has an outer side **3102**, and the outer side **3102** faces opposite to the ear **2000** when the earmuff **3100** covers the ear **2000**. The second microphone **820** is disposed on the outer side **3102** of the earmuff **3100**. Hence, the second microphone **820** is an exterior microphone of the headphone **3000b**.

Referring to FIG. 6B, the headphone **4000b** is similar to the headphone **4000** of FIG. 1B except that, the headphone **4000b** is further equipped with a second microphone **820** to receive a second noise **n2**. The plug **4100** of the headphone **4000b** has an outer portion **4102**, which is exposed from the ear **2000** when the inner portion **4101** is inserted into the ear **2000**. The second microphone **820** is disposed on the outer portion **4102** of the plug **4100**.

The second noise **n2** is another environmental noise, and the second microphone **820** generates a reference signal **r-a** based on the second noise **n2**. In operation, the first microphone **810** serves as an “error microphone” to provide the error signal **e-a**, while the second microphone **820** serves as a “reference microphone” to provide the reference signal **r-a**. The error signal **e-a** is provided to the audio processing device **1000b** through a FB path, while the reference signal **r-a** is provided to the audio processing device **1000b** through a feedforward (FF) path. The error signal **e-a** and the reference signal **r-a** are utilized by the audio processing device **1000b** to generate the desired cancelling signal **y-a**, so that the speaker **700** is able to provide desired first acoustic signal **ac1** based on the cancelling signal **y-a**.

FIG. 7A is a block diagram of the audio processing device **1000b** in FIGS. 6A and 6B. Referring to FIG. 7A, the audio processing device **1000b** is similar to the audio processing device **1000** of FIG. 2 except that, the audio processing device **1000b** further includes a RX front end **220** and a feedforward (FF) unit **410**, and the FB path **30** further includes a FB unit **330** (i.e., a third FB unit). In an embodiment, the FF unit **410** and the FB units **310**, **320** and **330** are implemented by execute instructions stored on a memory, using a processor. In the following content, the RX front end **210** can be called “a first RX front end”, and the RX front end **220** can be called “a second RX front end” when appropriate. The RX front end **220** is coupled to the FF unit **410** to form the FF path **40**, and the FF path **40** is disposed in a substantially parallel manner with the FB path **30**. Furthermore, the FB units **310**, **320** and **330** are coupled to one another in a parallel manner (i.e., coupled in shunt). That is, the audio processing device **1000b** has a “hybrid type” of circuit configuration including both FB path **30** and FF path **40**. In the “hybrid type” of circuit configuration, the FB units **310**, **320** and **330** in the FB path **30** function to process the error signal **e-d** derived from the first microphone **810**, while the FF unit **410** in the FF path **40** functions to process a reference signal **r-d** derived from the second microphone **820**.

More particularly, the second microphone **820** (i.e., the “reference microphone”) generates a reference signal **r-a** based on the second noise **n2** where the reference signal **r-a** is of analog type. Then, the RX front end **220** in the FF path **40** converts the reference signal **r-a** in analog domain into the reference signal **r-d** in digital domain. The FF unit **410** includes filters (not shown in FIG. 7A), and the reference signal **r-d** is used to generate input sequence for the filters in the FF unit **410**. Furthermore, the reference signal **r-d** is used to adjust coefficients of the filters in the FF unit **410**, so that FF unit **410** provides desired FF signal **f1**.

The FB signals **b1**, **b2** and **b3** from the FB units **310** to **330** are combined, by the mixer **380**, to form an overall FB signal **b0**. The audio processing device **1000b** further includes a mixer **580**, and the overall FB signal **b0** is combined with the FF signal **f1** by the mixer **580** to form the cancelling signal **y-d**. Moreover, the cancelling signal **y-d** in digital domain is converted, by the TX front end **100**, into the cancelling signal **y-a** in analog domain. That is, with the “hybrid type” of circuit configuration including both the FB path **30** and the FF path **40**, the cancelling signal **y-a** is derived based on the error signal **e-a** and the reference signal **r-a** through the FB path **30** and FF path **40**, respectively. Thereafter, the cancelling signal **y-a** is provided to the speaker **700** to generate the first acoustic signal **ac1**, and the first acoustic signal **ac1** is used to eliminate the first noise **n1**.

FIG. 7B is a block diagram of yet another example of audio processing device **1000c** of the disclosure. Referring to FIG. 7B, the audio processing device **1000c** also has a “hybrid type” of circuit configuration including both FB path **30** and FF path **40**. The audio processing device **1000c** of FIG. 7B is similar to the audio processing device **1000b** of FIG. 7A except that, the audio processing device **1000c** includes a plurality of FF units, FF units **410**, **420** and **430**. The FF units **410**, **420** and **430** are coupled in shunt; that is, the FF units **410** to **430** are coupled to one another in parallel. In an embodiment, the FF units **410**, **420** and **430** and the FB unit **310** are implemented by execute instructions stored on a memory, using a processor. The audio processing device **1000c** further includes a mixer **480** disposed in the FF path **40**, and FF signals **f1**, **f2** and **f3** from the FF units **410**, **420** and **430** are combined by the mixer **480** to obtain an overall FF signal **f0**.

Furthermore, compared with the audio processing device **1000b** of FIG. 7A, the audio processing device **1000c** of FIG. 7B includes a few number of FB unit, e.g., only one FB unit **310**. The FB signal **b1** from the FB unit **310** is combined with the overall FF signal **f0**, by the mixer **580**, to form the cancelling signal **y-d**, and the cancelling signal **y-d** is converted by the TX front end **100** into form the cancelling signal **y-a**.

FIG. 7C is a block diagram of further another example of audio processing device **1000d** of the disclosure. Referring to FIG. 7C, the audio processing device **1000d** is similar to the audio processing device **1000c** of FIG. 7B except that, the FB path **30** of the audio processing device **1000d** includes a plurality of FB units, FB units **310**, **320** and **330**. In an embodiment, the FF units **410**, **420** and **430** and the FB units **310**, **320** and **330** are implemented by execute instructions stored on a memory, using a processor. The FB signals **b1**, **b2** and **b3** are combined to form an overall FB signal **b0**. Then, the overall FB signal **b0** provided by the FB path **30** and the overall FF signal **f0** provided by the FF path **40** are combined to form the cancelling signal **y-d**.

FIG. 8 is a block diagram of further another example of audio processing device **1000e** of the disclosure. Referring to FIG. 8, the audio processing device **1000e** is similar to the audio processing device **1000c** of FIG. 7B except that, the audio processing device **1000e** includes only the FF path **40**, but does not include any FB path. That is, circuit configuration of the audio processing device **1000e** is not “hybrid type”. For the audio processing device **1000e**, the FF signals **f1**, **f2** and **f3** from the FF units **410**, **420** and **430** are combined to form the cancelling signal **y-d**.

According to the aforementioned examples of audio processing devices of the disclosure, a plurality of FB units is disposed in the FB path **30**, where the FB units are coupled to one another in a parallel manner (i.e., coupled in shunt).

With the shunt-coupled configuration of FB units, poles and overshoot of the equivalent transfer function of the audio processing device are remedied, hence howling phenomenon and noise added-on can be eliminated, and signal bandwidth can be increased. Furthermore, audio processing devices of the disclosure alternatively have a hybrid type of configuration including both FB path **30** and FF path **40**, where the FF path **40** receives the reference signal r-a based on the second noise n2 (i.e., the another environmental noise). With further aids of the reference signal r-a, more desirable cancelling signal y-a can be obtained, and the corresponding first acoustic signal ac1 will better reduce the first noise n1.

It will be apparent to those skilled in the art that various modifications and variations can be made to the disclosed embodiments. It is intended that the specification and examples be considered as exemplary only, with a true scope of the disclosure being indicated by the following claims and their equivalents.

What is claimed is:

1. An audio processing device, comprising:
    - a first active noise cancellation (ANC) filter, configured to generate a first anti-noise signal by applying only a time domain filtering to a full band of an error signal during an ANC period, the error signal is representative of audible sound at a target space; and
    - a second ANC filter, configured to generate a second anti-noise signal by applying only the time domain filtering to the full band of the error signal during the ANC period,
- wherein the first and second anti-noise signals are each simultaneously converted into an acoustic anti-noise signal to cancel environmental noise, or the first and second anti-noise signals in combination are converted into the acoustic anti-noise signal to cancel environmental noise,
- wherein the acoustic anti-noise signal is included in the error signal, and wherein the first ANC filter is connected to the second ANC filter in parallel,
- wherein the first ANC filter and the second ANC filter are independent of each other, and
- wherein the ANC period excludes a transition period in which both the first ANC filter and the second ANC filter temporarily generate the first anti-noise signal and the second anti-noise signal prior to only one of the first ANC filter and the second ANC filter generating the corresponding one of the first anti-noise signal and the second anti-noise signal.
2. The audio processing device according to claim 1, further comprising:
    - a receiving (RX) front end, configured to convert the error signal from an analog domain to a digital domain.
  3. The audio processing device according to claim 2, further comprising:
    - a mixer, configured to generate a cancelling signal associated with the acoustic anti-noise signal by combining the first anti-noise signal with the second anti-noise signal.

4. The audio processing device according to claim 3, further comprising:
  - a transmitting (TX) front end, configured to convert the cancelling signal from a digital domain to an analog domain.
5. The audio processing device according to claim 4, wherein the first ANC filter and the second ANC filter are coupled to the RX front end, and the first ANC filter, the second ANC filter and the RX front end define a feedback (FB) path, wherein the FB path provides the cancelling signal to the TX front end.
10. The audio processing device according to claim 1, wherein each of the first ANC filter and the second ANC filter is a feedback (FB) filter, or each of the first ANC filter and the second ANC filter is a feedforward (FF) filter.
15. The audio processing device according to claim 1, wherein the first ANC filter is one of a feedback (FB) filter and a feedforward (FF) filter, and the second ANC filter is the one of a FB filter and a FF filter, the audio processing device further comprising:
  - a third ANC filter, being the other of a FB filter and a FF filter.
20. The audio processing device according to claim 1, wherein each of the first ANC filter and the second ANC filter is a feedback (FB) filter, the audio processing device further comprising:
  - a third ANC filter, being a feedforward (FF) filter, configured to generate a third anti-noise signal based on a reference signal from an exterior microphone of a headphone; and
  - a fourth ANC filter, being a FF filter, configured to generate a fourth anti-noise signal based on the reference signal,
25. The audio processing device according to claim 1, wherein the third ANC filter is connected to the fourth ANC filter in parallel.
30. The audio processing device according to claim 1, further comprising:
  - a receiving (RX) front end, configured to convert the error signal from an analog domain to a digital domain;
  - a first mixer, configured to generate an overall FB signal by combining the first anti-noise signal and the second anti-noise signal; and
  - a second mixer, configured to generate an overall FF signal by combining the third anti-noise signal and the fourth anti-noise signal.
35. The audio processing device according to claim 9, further comprising:
  - a third mixer, configured to generate a cancelling signal associated with the acoustic anti-noise signal by combining the overall FB signal and the overall FF signal; and
  - a transmitting (TX) front end, configured to convert the cancelling signal from the digital domain to the analog domain.
